UNITED STATES PATENT OFFICE.

EDWARD J. CONDON, OF DIXON, ILLINOIS.

SIGNAL.

No. 841,767.

Specification of Letters Patent.

Patented Jan. 22, 1907.

Application filed November 18, 1905. Serial No. 287,208.

To all whom it may concern:

Be it known that I, EDWARD J. CONDON, a citizen of the United States, residing at Dixon, in the county of Lee and State of Illinois, (whose post-office address is Dixon, Illinois,) have invented a new and useful Improvement in Railway-Signals, of which the following is a specification.

My invention relates to signals and signal systems, relating particularly to railroad signals, with special reference to that class of signals which are automatically actuated by the passage of the railway-train.

My invention is particularly adapted for employment in connection with what is known as the "block-signal" system.

I have found by experience that the efficiency of electrically-thrown signals for railway service is frequently impaired, due to the short circuits caused by the accumulation of water or ice or to other causes and also due to the fact that the mechanism of the signals must be so delicately adjusted that the same readily becomes disarranged.

The signals which are operated wholly by mechanical means must necessarily be constructed so large and the quantity of material required rendered so great that their operation in blocks or series is substantially impossible.

It is one of the objects of my present invention to combine the advantages of mechanically-operated signals and electrically-operated signals, eliminating the undesirable features of each, and to this end I provide a system in which the signals are actuated by mechanical means, while electrical means are employed for the purpose of signal communication.

My invention contemplates a system comprising a plurality of independently-actuated signals so connected that the release of one is effected through the actuation of the next succeeding signal.

In the preferred embodiment of my invention I employ fluid-pressure for setting the signal and electrically-operated means for releasing the same when the next succeeding signal is actuated. Generally speaking, my invention comprises a signal actuated through the medium of the fluid-pressure supplied by the passing of the train, an automatic lock for retaining the signal in the position to which it has been moved by said fluid-pressure, and electrically-operated means for operating said lock to release the

signal when the next succeeding signal has been actuated by the train.

I have illustrated the preferred embodiment of my invention in the accompanying drawings, in which—

Figure 1 is a side elevation of the signal embodying my invention, showing the position of the car or train relative to the signal-actuating mechanism. Fig. 2 is a sectional view of the fluid-compressor, taken on the line 2 2 of Fig. 3. Fig. 3 is a plan view of the fluid-compressor. Fig. 4 is a view similar to Fig. 3, with the parts thereof in section. Fig. 5 is a sectional view taken on line 5 5 of Fig. 4. Fig. 6 is a front elevation of the device carried by the car for operating the fluid-compressor device. Fig. 7 is a plan view of the device. Fig. 8 is a sectional view on line 8 8 of Fig. 6. Fig. 9 is a detail view showing the catch for locking the operating device carried by the car in position. Fig. 10 is an enlarged detail view of the top of the signal, showing the operating mechanism, the casing of the signal being shown in section. Fig. 11 is a rear view of the part shown in Fig. 6, the casing being shown in section. Fig. 12 is a plan view of the part shown in Fig. 6, the casing being shown in section. Fig. 13 is a detail view of the cam carried on the semaphore-shaft. Fig. 14 is a front elevation of the box containing the device for rendering the signal inoperative. Fig. 15 is a sectional view taken on line 15 15 of Fig. 14. Fig. 16 is a sectional view taken on line 16 16 of Fig. 14. Fig. 17 is a sectional view of the valve for rendering the signal-actuating means inoperative. Fig. 18 is a transverse sectional view taken on the line 18 18 of Fig. 15. Fig. 19 is a sectional view taken on line 19 19 of Fig. 18 looking in the direction of the arrow. Fig. 20 is a section taken on the same line looking in the opposite direction. Fig. 21 is a section taken on line 21 21 of Fig. 19, and Fig. 22 is a diagrammatic view showing the circuit arrangement of my device when the same is used in a block system.

In the preferred embodiment of my invention upon a suitable post or standard I mount a box or casing 2, having journaled in the sides thereof a shaft 3, which extends through the casing and has one end projecting beyond one side of the same for supporting a semaphore-arm 4. This arm is of the usual construction and is so keyed upon the shaft that rotating of the shaft rocks the arm in a vertical plane. A crank-arm 5 for oper-

ating the shaft 3 is keyed upon the same upon the inside of the casing and has its outer end connected by a link 6 with the end of a rod 7 of the piston 8, an opening 9 being formed in the bottom of the casing to permit the passage of the link. The piston 8 operates in a vertically-arranged cylinder 10, secured in any desired manner upon the standard 1 and within a casing 11, which extends from the bottom of casing 2 and completely incloses the cylinder. By this arrangement of the casings 2 and 11 all the operative parts of the semaphore are entirely inclosed and protected against the elements. Normally the piston 8 is near the bottom of its cylinder 10, and when in this position the outer end of the semaphore-arm is down or in a safety position. When the piston is forced up in its cylinder, it rocks the arm 5 through the link 6 and raises the outer end of the semaphore-arm 4 to place the arm in a horizontal or danger position.

Fluid-pressure is supplied to the cylinder 10 for operating the piston 8 through a pipe 12, which connects with the bottom of the cylinder and extends through the cut-out box 13 to the air-compressor 14. The compressor is preferably operated by the passing of the train and to this end comprises a cylinder 15, arranged horizontally and in proximity to the tracks, and a piston 16, which is operated by the passage of the train. The cylinder 15 is carried at one end by a vertical support 17, which forms one of the ends of the cylinder and extends upwardly from a suitable base 18. At the opposite end of the base 18 is a second vertical support 19, which has an opening 20 therein concentric with an opening 21 in the support 17, and in these two openings operates the rod 22 of the piston 16. The piston 16 has the usual leather collar, which collapses as the piston is moved to the left and allows the air to pass to the front of the piston. As soon as the piston moves forward the collar expands and the air admitted through the ports 15^a and past the piston is compressed.

The upper side of the cylinder 15 is preferably flattened and has secured thereon a pair of guide-bars 24, channeled on their under sides, as at 25, to form a channel in which operates the reciprocating bar 26. This bar extends the length of the cylinder and the base 18, having its rear end supported in guides 27 on the support 19, and is connected at an intermediate point with the piston-rod 22 by a downwardly-projecting lug 28, provided with an opening 29, through which the rod 22 passes. Collars 30 are secured upon the piston-rod 22 upon either side of the lug 28, whereby the piston 16 will reciprocate with the bar 26. A buffer 31 is interposed between the lug 28 and support 17 to take up the jar resulting from the return of the rod to its normal position by the coil-spring 32,

mounted upon the piston-rod 22 and interposed between the support 19 and the lug 28.

The bar 26 is moved rearwardly by the engagement with a vertical roller 33, carried upon a pin 34, mounted upon the forward end thereof, by a member carried upon the engine or one of the cars. To prevent the pin from becoming bent and to aid in holding the same rigidly, I provide a rearwardly-extending brace 35, fastened at one end to the upper end of the pin and bolted at its opposite end to the bar 26.

While any form of contacting device may be employed upon the car for reciprocating the bar 26, I preferably provide an arm or rod 36, having its forward and rear ends turned inwardly and bent to form the pivot-pins 37, which are mounted in blocks 38 and 39, secured upon a base-plate 40, which in turn is adapted to be secured to the truck of the car. The inturned portion 41 of the arm is longer than the opposite portion, whereby the arm will incline outwardly. By pivotally mounting the arm upon its base when it is not in use it may be raised, as shown in dotted lines in Fig. 6, the portion 41 being adapted to fit within a vertical groove 42 formed in the block 39. A cam 43, pivoted to the block 39 and provided with a catch 44 serves to hold the arm either in its operative or inoperative position, and a support 45, on which the portion 41 rests, supports the arm when it is dropped down to operative position.

In operation as the car passes the signal the arm 36 engages the roller 33 and forces the bar 26 rearward, and with it the piston-rod 22 and piston 16, against the action of the coiled spring 32. As soon as the roller is released from engagement with the arm 36 the coiled spring forces the bar 26, and with it the piston 16, forward, compressing the air and forcing the same through the port 46 in the forward end of the cylinder and through the pipe 12 to the cylinder 10. This raises the piston, which by the link 6 and arm 5 rocks the shaft 3 to raise the semaphore-arm 4 to a danger position, where it is held by a lock until the train passes out of the block controlled by the signal.

It will be understood that while I have described air as being the fluid under pressure for operating my device other fluids, such as water or oil, may be used, if so desired.

Mounted upon shaft 3, and preferably formed integrally with the hub of the arm 5, is a rearwardly-extending lug 47, which is adapted to be engaged by a catch 48, carried upon the vertical arm 49 of a bell-crank lever pivoted at 50 between the two vertical uprights 51, supported upon a plate 52, secured to the bottom of the casing 2. The end of the horizontal arm 53 of the bell-crank lever has connected thereto the core 54 of a solenoid 55, carried by the bracket 56, secured to

the side of the casing 2, and when current is admitted to the winding of said solenoid, causing the same to attract or raise its core, the bell-crank lever will be operated to cause 5 the catch 48 to release the lug 47 and permit the arm 4 to fall.

A second bell-crank lever is pivoted at 57 between the uprights 51, the horizontal arm 58 of which has a weight 59 secured at its outer end. The vertical arm 60 of the bell-crank lever is provided with an inwardly-projecting V-shaped shoulder 61, which is adapted to be engaged by the double cam 62, carried upon the lug 47. The arm 60 and 15 the arm 49 each carry spring-contacts 63 and 64, respectively. The cam 62 is so arranged that as the semaphore-arm is moved up by its piston the lug will be moved downwardly, and due to the fact that the arm is violently 20 thrown up past the horizontal the cam will be moved entirely below the shoulder 61, permitting the contact 63 to engage the contact 64 for a short period until the arm drops back to normal, when the cam will engage the shoulder 61, separating the contacts, and at 25 the same time the catch 48 will engage over the lug 47, holding the semaphore-arm against further downward movement.

The semaphore-signals are arranged to be 30 used in series and the magnets 55 thereof are arranged in a normally open circuit, so that the arm 4 will after it has been moved up remain at a danger position until the train has passed the next succeeding semaphore and 35 operated the same. The operation of this signal will cause the contacts 63 and 64 thereof to close, as has just been described, thereby momentarily closing the circuit through the solenoid 55 of the preceding signal, which 40 will cause the same to raise the core 54 and move the arm 49 of the bell-crank lever to release the catch 48, permitting the semaphore-arm to drop down to safety position.

My signals, as previously described, are arranged to be used in series in what is known 45 as the "block system," and in order that any one of the signals may be cut out of service in the pipe 12 at a point intermediate of the cylinder 10 and the cylinder 15 I provide a 50 valve 65, operating in a chamber 66. This chamber 66 is connected at one end to that portion of the pipe 12 which leads to the cylinder 10 and communicates when the opening 67 of the valve is turned in proper position through said opening with the portion of the pipe which leads to the cylinder 15. When the valve is in this position, the signal 55 is operative. By turning the valve so that the opening 67 connects the portion of the 60 pipe which leads to the cylinder 15 with the port 68 leading to the atmosphere the signal is rendered inoperative, as the compressed air will then instead of passing to the cylinder 10 for operating the semaphore-signal escape 65 to the atmosphere. The valve 65 is

mounted upon a suitable shaft journaled in the casing 69, and at one end of this shaft is carried a suitable signal 70, which when the semaphore-signal is rendered inoperative indicates such a fact. Upon the end of the 70 shaft opposite that which carries the signal 70 an operating-handle 71 is provided, and this handle also carries contacts 72 and 73, which contacts are arranged to engage the terminals 74, 75, 76, 77, 78, and 79, as will be hereinafter more fully pointed out. These terminals are suitably mounted upon a bracket 80, which is supported within a casing or cut-out box 13. This cut-out box also contains 75 the cut-out valve for rendering the signal inoperative and is so provided that all the valve parts of the cut-out are inclosed and protected against injury, an opening 81 being provided therein through which the signal 70 may pass, a door 82 being also provided 80 whereby access may be obtained to the handle 71 for operating the cut-out.

In Fig. 22 I have illustrated diagrammatically a circuit arrangement for the electrical portion of a series of semaphores in the block 90 system. In this figure, A will be used to designate the first semaphore-signal; B, the second semaphore-signal; C, the third semaphore-signal; D, the fourth semaphore-signal, and E the fifth semaphore-signal. 95 The signal A does not necessarily have to be provided with contacts 63 and 64, as there is no preceding signal to be dropped upon the passage of the train thereby. It is, however, provided with a solenoid-magnet 55 for operating the release. One terminal of this magnet is connected by conductor 83 with one terminal of the battery 84. The opposite terminal of the magnet 55 is connected by conductor 85 with the contact 63 of the signal B, and the opposite terminal of the battery 84 is connected by conductor 86 with the contact 64 of the signal B. It will therefore be seen that as soon as the signal B is operated, permitting the two contacts 63 and 64 100 to come into engagement, circuit will be closed from the battery 84 by conductor 83 through the magnet 55 of the signal A, by conductor 85 to contact 63, thence to contact 64, and by conductor 86 back to the opposite 105 side of the battery 84. The closing of this circuit, as before mentioned, permits the magnet 55 to attract the arm 53, causing the catch 48 on the arm 49 of the bell-crank lever to release the semaphore-arm 4 of the signal 110 A. The conductor 85 has a branch 87, which is connected with the terminal 78 of the switch of the cut-out for the signal B, and the conductor 86 has a branch 88 connected with the terminal 79 of the switch of the cut-out 115 for the signal B. The magnet-windings 55 of the signal B have one terminal connected by conductor 89 with the terminal 75 of the cut-out switch, and the opposite terminal of the magnet 55 of the signal B is connected by 120 125 130

conductor 90 with the terminal 76 of the cut-out switch. The terminal 77 of the cut-out switch is connected by conductor 90 with one side of the battery 92, and the terminal 74 of the switch is connected by conductor 93 with the contact 63 of the signal C, the contact 64 thereof being connected by conductor 55 with the opposite side of the battery 92. By this arrangement when the signal is operated 5 and the cut-out switch is in its normal position, when the signal C is operated the contact-terminals 63 and 64 temporarily make contact and circuit is closed from one terminal of the battery, over conductor 91, to the terminal 77 of the cut-out switch, then across the contact 73 to terminal 76, thence by conductor 90 through the windings 55 of the switch B, by conductor 89 to the terminal 75, across the contact 72 to the terminal 74, thence 10 by conductor 93 to contact 63 of the signal C, the contact 64, and thence by conductor 95 to the opposite side of the battery 92. This energizes the winding of the magnet 55, which attracts the arm 53 and causes the catch 48 15 to release the semaphore-arm 4 of the signal B. In event it is desired to cut out the signal B between the signal C and the signal A, the cut-out switch is moved until the contacts 72 and 73 connect the terminals 74, 75, and 78 20 and 79, 76, and 77. Under these circumstances the circuit when the contacts 63 and 64 of signal C are operated will be closed from the battery 92 by conductor 91 to the terminal 77, thence across the contact 73 to the terminal 79, thence by conductor 88 through the battery 84 by conductor 83, through the windings of the magnet 55 of the signal A by conductors 85 and 87 to the terminals 78, across the contact 72 to terminal 74, by conductor 93 to the contact 63, and by contact 64 and conductor 55 to the opposite side of the battery 92. In this manner the signal B is cut out of service, as there is a normally closed branch circuit established to the magnet 55 25 thereof, whereby the magnet will always be permanently energized and render the catch 48 of the signal B inoperative.

Having thus described my invention, it will be of course understood that various 30 modifications may be made therein without departing from the spirit thereof, and I do not wish to be limited to the specific details of construction as illustrated and described.

Having thus described my invention, what 35 I claim as new, and desire to secure by Letters Patent, is—

1. In a device of the character described, the combination with a semaphore-arm, of a lock for holding said arm in its thrown position, a switch member carried by said lock, a second switch member having a tendency to move toward said first-mentioned switch member, means carried by said arm to normally hold said switch members apart and to

permit the same to momentarily engage when 65 the arm is thrown.

2. In a device of the character described, the combination with a semaphore-arm, having a rearwardly-extending projection carried thereby, a latch for engaging said projection when the arm is thrown, a switch member carried by said latch, and a second switch member having a tendency to move toward said first member, said projection being arranged to hold said members apart and to 70 permit the same to momentarily engage when the arm is thrown.

3. In a device of the character described, the combination with a signal of a motor operated by fluid-pressure for actuating said 80 signal and carried by the support for said signal, a compressor, a spring for operating said compressor, means operated by the passage of the train for storing energy in said spring, and a connection extending between said 85 compressor and said motor for transmitting the fluid under pressure to said motor.

4. In a device of the character described, the combination with a semaphore-arm, of a gravity-catch for retaining said arm in its 90 thrown position, an electromagnet in a normally open circuit for causing the release of said arm, and a switch operated by the next succeeding semaphore-arm for momentarily closing the circuit through said magnet.

5. In a device of the character described, the combination with a series of signals each having means operated by fluid under pressure for throwing the same to the danger-point means operated by the passage of the 100 train for supplying fluid under pressure, means for retaining said signals in their danger position, means for releasing said signal when another of said series of signals is operated, and means for rendering any one of said 105 signals inoperative without rendering the remaining signals inoperative.

6. In a device of the character described, the combination with a plurality of signals arranged in series each having means operated 110 by fluid-pressure for throwing the same to the danger-point and means operated by the passage of the train for supplying fluid under pressure, means for retaining each signal in its thrown position, means operated by the 115 passage of the train past another of the signals in series for releasing the signal, means for cutting out any one of said signals and means whereby when one of said signals is cut out the signal immediately preceding the 120 same will be so connected with the signal immediately succeeding the same that the operating of the succeeding signal by the passage of the train will release the preceding signal.

7. In a device of the character described, 125 the combination with a plurality of signals arranged in series each having means operated by fluid-pressure for throwing the same

- to the danger-point, and means operated by the passage of the train for supplying fluid under pressure, means for retaining each signal in its thrown position, means operated by the passage of the train past another of the signals in series for releasing the signal, means for cutting out any one of said signals, and electrically-controlled means whereby when one of said signals is cut out the signal immediately preceding the same will be so connected with the signal immediately succeeding the same that the operating of the succeeding signal by the passage of the train will release the preceding signal.
8. In a device of the character described, the combination with a plurality of signals arranged in series each having means operated by fluid-pressure for throwing said signals, means operated by the passage of the train for supplying fluid under pressure means for retaining said signal in a thrown position, an electrically-controlled means for releasing said signal arranged to be operated by the throwing of another of the signals in the series, means for rendering any one of the signals in the series inoperative, and means operated by said last-mentioned means whereby when the signal immediately preceding the same is thrown, it will remain thrown until the signal immediately succeeding the same is operated by the passage of the train.
9. In a device of the character described, the combination with a signal, of a cylinder having a spring-actuated piston and arranged in proximity to the tracks, an auxiliary cylinder having a tubular connection with said first-mentioned cylinder and arranged in proximity to said signal and a connection between said auxiliary cylinder and the signal.
10. In a device of the character described, the combination with a signal, of a pair of cylinders one arranged in proximity to said signal and the other arranged in proximity to the tracks; the cylinder in proximity to the tracks having a spring-actuated piston-rod having means operated by the passing of the train for causing said piston to be actuated for placing fluid under pressure means whereby the fluid-pressure will be delivered to the other cylinder, and means whereby said first-mentioned cylinder will operate the signal.
11. In a device of the character described, the combination with a plurality of semaphore-arms arranged in series each having means for rocking the same upon the passage of the train, means for retaining the same in a substantially horizontal position, an electromagnet for operating said retaining means to release said arms, and means operated by the rocking of the arm of said signals for closing the circuit through the electromagnet of the preceding signal.
12. In a device of the character described, the combination with a plurality of semaphore-arms arranged in series, means for operating each one of said arms as the train passes the same, means for retaining said arms in their operated position, electrically-operated means for releasing said signals, and means operated by the next preceding arm for closing the circuit of said electrically-operated means of the arm previously passed by the train.
13. In a device of the character described, the combination with a plurality of signals arranged in series of means operated by fluid under pressure for throwing said signals, means for retaining said signals in their thrown position, a releasing-magnet for each of said signals in a normally open circuit, means for rendering any one of said signals inoperative, and means operated by said means for connecting the next preceding releasing-magnet in a circuit including the releasing-magnet of the next succeeding signal.
14. In a device of the character described, the combination with a signal, of means operated by fluid under pressure for throwing said signal, a fluid-compressor for supplying fluid to said means, comprising a cylinder, a piston, a spring for moving said piston in a direction to compress the fluid, a reciprocating arm connected with said piston and means carried by the train for operating said arm to move the piston in an opposite direction.
15. In a device of the character described, the combination with a signal, of means operated by fluid under pressure for throwing said signal, a compressor for supplying said means with fluid under pressure, and comprising a cylinder, a piston operating in said cylinder, a spring for moving said cylinder in one direction a reciprocating arm connected with said piston for moving the same in the opposite direction, and an inclined arm carried by the rolling-stock for engaging said reciprocating arm for operating the same.

In testimony whereof I have signed my name to this specification in the presence of two subscribing witnesses.

EDWARD J. CONDON.
